UNITED STATES PATENT OFFICE

SARAH M. HODGE, OF CHICAGO, ILLINOIS.

DESIGN FOR LADIES' AND CHILDREN'S HOODS.

Specification forming part of Design No. **11,527**, dated November 25, 1879; application filed November 3, 1879.
[Term of patent 3½ years.]

To all whom it may concern:

Be it known that I, SARAH M. HODGE, of Chicago, in the county of Cook and State of Illinois, have originated and designed Ladies' and Children's Hoods, of which the following is a full, clear, and exact description, reference being had to the accompanying photographic illustration, making part of this specification.

The design is shown in the accompanying photograph of a child's cap or hood.

The design consists in the ornamentation of the body produced by the open-work interlooped and enchain'd threads, the same being crochet-work with a loose stitch, with silk or cotton thread, and lined with colored cloth or silk, thereby producing a light, rich, and handsome effect. Around the front and lower

edges lace is attached, and the hood otherwise ornamented by lace and ribbon. The thread ornamentation may be of any color.

Having thus described my invention, what I claim as my invention is—

1. The design for ladies' and children's hoods, in which the body is ornamented by open-work interlooped and enchain'd threads, substantially as shown and described.
2. The design for ladies' and children's hoods, in which the body is ornamented by interlooped threads, with an edging of lace, substantially as shown and described.

SARAH MATILDA HODGE.
